(57) **CLAIM**

The ornamental design for a functional trainer adjustable handle, as shown and described.

DESCRIPTION

FIG. 1 is a front perspective view of a functional trainer adjustable handle showing my new design; FIG. 2 is a rear perspective view thereof; FIG. 3 is a front elevational view thereof; FIG. 4 is a rear elevational view thereof; FIG. 5 is a left side view thereof; FIG. 6 is a right side view thereof; FIG. 7 is a top plan view thereof; FIG. 8 is a bottom plan view thereof; FIG. 9 is a front perspective view of the functional trainer adjustable handle in a second state; FIG. 10 is a front perspective view of the functional trainer adjustable handle in a third state; and, FIG. 11 is a front perspective schematic view of the functional trainer adjustable handle in a usage environment. The broken lines in the FIGS. 1-10 are for the purposes of illustrating portions of the functional trainer adjustable handle and the FIG. 11 is directed to environment only, all broken lines form no part of the claim design.

1 Claim, 11 Drawing Sheets
